COLLAPSIBLE DISPLAY DEVICE

Application filed April 10, 1931. Serial No. 529,184.

This invention relates to display devices, and has particular reference to devices of this character which are collapsible to facilitate their storage and shipment when in a collapsed condition.

The invention broadly aims to provide a display device of the indicated character which when set up is self supporting and which includes a panel capable of being disposed at varying inclinations with respect to a supporting surface.

More specifically, the invention resides in a collapsible self supporting display device which includes a longitudinally rollable panel and a foldable member constituting a common means for stretching and maintaining the panel in a stretched condition and for supporting the panel from a substantially horizontal supporting surface.

Other objects of the invention reside in a device of the indicated character which employs few and simple parts, capable of economical production and assemblage and which efficiently perform their intended function.

With the above recited and other objects in view, reference is had to the following description and accompanying drawing, in which there is exhibited one example or embodiment of the invention, while the claims define the actual scope of the same.

In the drawing:

Figure 1 is a perspective view of the device in its set up condition as viewed from the rear.

Figure 2 is a similar view of the device in its collapsed condition.

Figure 3 is a longitudinal sectional view through the panel stretching and supporting member in its folded condition.

Referring to the drawing by characters of reference, 5 designates a flexible panel of any suitable material which is provided with means 6 and 7 at its opposite ends which renders the same rigid transversely at said ends and which in the present instance is indicated as transverse brace strips of any suitable material. The device further includes foldable means engageable with said first means for stretching and bracing the panel longitudi-

nally and for supporting the same upon a horizontal supporting surface and at an inclination thereto. The said foldable means embodies a brace member designated generally by the reference character 8, which member is adjustable in length and is engageable with the brace strips 6 and 7 to stretch and maintain the panel in a longitudinally stretched condition. The said foldable means further includes a supporting leg 9 pivotally carried by the brace member 8 whereby it may be folded parallel thereto, so that the panel may be rolled about the leg and brace member in the manner illustrated in Figure 2. As particularly illustrated, the brace member includes a pair of slidably connected sections 10 and 11, the former having a longitudinal slot 12 and the latter a longitudinal slot 13. A connecting and guiding element, such as a rivet 14, extends through an aperture 15 in the section 11 and through the slot 12 in the section 10. A threaded bolt 16 extends through an aperture 17 in the section 10 and through the slot 13 in the section 11, and said bolt also extends through an aperture 18 in the leg 9 and protrudes therefrom and receives a thumb nut 19. The section 10 is provided at one end with a reduced extremity 20 and the opposite end of the section 11 is formed with a reduced extremity 21, while the brace strips 6 and 7 are respectively provided with receiving apertures 22 and 23 to accommodate the extremities 21 and 20.

With the device in the folded or roller condition illustrated in Figure 2, the setting up of the same is accomplished by unrolling the panel 5, loosening the thumb nut 19, engaging the extremities 20 and 21 in the keeper openings 22 and 23 and extending or lengthening the brace member 8 by sliding the sections 10 and 11 relatively until the panel 5 is stretched longitudinally, at the same time swinging the supporting leg 9 to the desired angularity and then tightening the thumb nut 19. It will thus be seen that the bolt 16 and its nut 19 constitute a common means for assisting in the guiding of the sections 10 and 11, for pivotally associating the supporting leg 9 therewith and for maintaining the

sections 10 and 11 and leg 9 in adjusted position while indirectly holding the panel 5 in its stretched condition. When thus set up, the device may be supported on a substantially horizontal surface so that the panel 5 presents an outer surface which may bear advertising matter or may support various articles for display. To collapse the device, it is only necessary to loosen the thumb nut 19, slide the sections 10 and 11 relatively to disengage the extremities 20 and 21 from the keeper openings 22 and 23 in the brace strips 6 and 7, then fold the leg to a parallel position to the brace member 8. The brace member 8 and leg 9 may now be rolled in the panel as illustrated in Figure 2 so that the device occupies a minimum space for storage and shipment. The device may be found useful in various fields and for various purposes to which a device of this character may be adapted, and no limitation is intended to the use or to the precise structural details herein exhibited, as it is to be understood that modifications and variations which properly fall within the scope of the claims may be resorted to when desired.

What is claimed is:

1. A display device including a flexible panel, transverse brace strips at opposite ends thereof rendering the same transversely rigid at said ends, a brace member adjustable in length engageable with the brace strips for stretching and maintaining the panel in a longitudinally stretched condition, said brace member including a pair of longitudinally slotted sections, means extending respectively from each section through the slot of the other section to connect the sections for relative sliding movement, a supporting leg pivotally carried by one of said means and a device engaging said means for clampingly holding the sections in longitudinally adjusted relation and the leg in parallel or various angularly adjusted relations to the brace member.
2. In a display device, a longitudinally rollable flexible panel, rigid transverse elements secured to the opposite ends of said panel, a brace member engageable with said elements and longitudinally extensible to stretch and maintain the panel in longitudinally stretched condition, a supporting leg and a common means for respectively holding the brace member extended, pivoting the leg to the brace member and retaining said leg in various relatively adjusted angular positions with respect to the brace member.
